CLAIM

The ornamental design for a bird/fish ornament, as shown and described.

DESCRIPTION

FIG. 1 is a perspective view of a bird/fish ornament, showing the new design;

FIG. 2 is a front view thereof showing a fish orientation, with the opposite side being a mirror image thereof; and, FIG. 3 is a front view thereof showing a bird orientation with the opposite side being a mirror image thereof.

The broken lines illustrate portions of the bird/fish ornament and form no part of the claimed design.
